Primary Examiner — Elizabeth J Oswecki*(74) Attorney, Agent, or Firm* — Mintz Levin Cohn Ferris Glovsky and Popeo, P.C.; Kongsik Kim; Jonathon Western(57) **CLAIM**

The ornamental design for a nonskid pad for shoes, as shown and described.

DESCRIPTION

FIG. 1 is a perspective view of a nonskid pad for shoes showing my new design.

FIG. 2 is a front view of the nonskid pad of FIG. 1.

FIG. 3 is a rear view of the nonskid pad of FIG. 1.

FIG. 4 is a left side view of the nonskid pad of FIG. 1.

FIG. 5 is a right side view of the nonskid pad of FIG. 1.

FIG. 6 is a top view of the nonskid pad of FIG. 1.

FIG. 7 is a bottom view of the nonskid pad of FIG. 1; and, FIG. 8 is another perspective view of the nonskid pad of FIG. 1, shown in a used condition on a shoe sole shown in broken lines.

The broken lines shown in the drawings represent portion of the nonskid pad for shoes that form no part of the claimed design.

1 Claim, 8 Drawing Sheets(56)
